(57) **CLAIM**

The ornamental design for a voice recording/reproducing apparatus, as shown and described.

DESCRIPTION

FIG. 1 is a perspective view showing a voice recording/reproducing apparatus that is our novel design, as seen obliquely from the front right upper side thereof.

FIG. 2 is a perspective view as seen obliquely from the rear right lower side thereof;

FIG. 3 is a front view thereof;

FIG. 4 is a rear view thereof;

FIG. 5 is a plan view thereof;

FIG. 6 is a bottom plan view thereof;

FIG. 7 is a right side view thereof;

FIG. 8 is a left side view thereof; and,

FIG. 9 is a front view thereof, with the body and the battery storing part shown separated.
